[57] CLAIM

The ornamental design for a wall mounted rack or the like, substantially as shown and described.

DESCRIPTION

FIG. 1 is a front elevational view of a wall mounted rack or the like embodying my new design, with the back being plain and unornamental;

FIG. 2 is a side elevational view thereof with the opposite side being a mirror image of the side shown; and
FIG. 3 is a top plan view thereof, the bottom being a mirror image except for the hooks.
